UNITED STATES PATENT OFFICE.

JOHN ROGERS, OF NEW CANAAN, CONNECTICUT.

DESIGN FOR A GROUP OF STATUARY.

Specification forming part of Design No. **11,486**, dated November 4, 1879; application filed October 9, 1879.
[Term of patent 14 years.]

To all whom it may concern:

Be it known that I, JOHN ROGERS, of New Canaan, in the county of Fairfield and State of Connecticut, have originated a new Design for a Group of Statuary, of which the following is a full, clear, and exact description, reference being had to the accompanying photographic illustration, making part of this specification.

The group, which is designated "The Balcony," represents a lady and little child in a balcony, which is raised on a wall a short distance from the ground below, where there are some street musicians and a dog. One of these musicians is a girl, who is kneeling down. She has her tambourine under her left arm, and is holding up her right hand toward the dog, which she is making sit up. He has some object balanced on his nose. The other musician is a boy, who has a violin under his

left arm, and is holding his hat up with his right hand to receive a piece of money which the little boy on the balcony-railing is reaching down to drop in. The lady is standing in the balcony and supporting the child.

What I claim as my invention is—

The design for a group of statuary representing a lady standing in a balcony and supporting a child on the railing of the balcony, who is reaching down to drop a piece of money in the hat of a boy who stands on the ground below, and by whose side is a dog sitting on its haunches and balancing something on its nose, while a girl is kneeling by its side and directing him, substantially as described, and shown in the accompanying illustration.

JOHN ROGERS.
